UNITED STATES PATENT OFFICE.

EDWIN CURTIS CLARK, OF DELANO, CALIFORNIA.

AUTOMOBILE-SIGNAL.

1,343,248.

Specification of Letters Patent. Patented June 15, 1920.

Application filed April 4, 1919. Serial No. 287,443.

To all whom it may concern:

Be it known that I, EDWIN CURTIS CLARK, a citizen of the United States, residing at Delano, in the county of Kern and State of California, have invented certain new and useful Improvements in Automobile-Signals, of which the following is a specification.

This invention relates to signals, and more especially to those intended for use on an automobile whereby the driver may signal to a person behind what are his intentions as to stopping or turning.

The primary object of the invention is to store the structure when not in use in small space, and to amplify its size when it is thrown into an active position.

Another object is to put the actuating mechanism within reach of the operator.

Other objects will appear in the following specification and claims.

In the drawings—

Figure 1 is an elevation of this signal as the operator sees it, with the casing partly broken away, and the signal housed. Fig. 2 is a similar elevation with the casing in section and the signal displayed.

Fig. 3 is a horizontal section on the line 3—3 of Fig. 1.

Fig. 4 is an edge view of the signal within its casing, and Fig. 5 is an enlarged cross section on the line 5—5 of Fig. 4.

The letter G designates the glass and F the frame of an ordinary windshield. Attached to one edge of the frame as by a screw 1 is a bracket 2 supporting an upright casing 3 which is open at that side remote from the wind shield frame and is otherwise of a size to contain the signal proper as shown in Fig. 4. The signal as here illustrated is made up of three blades, respectively indicated by the numerals 11, 21 and 31. When this signal is housed, the blade 31 rests against a spring 4 within the housing, and the lower end of the main blade projects through a slot in the bottom of the housing or casing and between two ears 5 wherein it is pivoted at 6, its lower end constituting an arm 7 which is connected with the actuating mechanism. The latter as herein shown consists of a link 8 pivotally connecting the lower end of the arm with a slide rod 9 mounted in guides 10 in the bottom of the frame F and having a handle 12 at its inner end, the rod by preference having stops 13 adapted to be

passed through the guides or set adjacent them to hold the signal in either position. A spring 14 connects the outer end of the rod at the point 15 with a point 16 in the rod 7 as shown. When the rod is moved outward to the position illustrated in Fig. 1 and the stop 13 rests against the inner guide, the link 8 pushes the arm 7 outward and throws the body of the inner or main blade upward into the casing 3 as shown.

The other blades are pivoted to the main blades on a common pivot 19 which is some distance above the main pivot 6 and moves into the casing as the blade is housed. The intermediate blade 21 stands between the main blade 11 and the outer blade 31. Both these blades 21 and 31 have short arms 22 beneath their pivot 19 adapted to contact with the bottom 23 of the casing or housing 3, for a purpose yet to appear. The outer end of the main blade 11 has a lip 24 and a loop 25. The outer end of the intermediate blade 21 has a pin 26 in said loop and a lip 27 as seen at the right of Fig. 2. The outer end of the outer blade 31 has a pin 28 working in a loop 29 which is at the outer end of the intermediate blade. The lips 24 and 27 prevent the folding or collapsing of the blades as seen in Fig. 1, whereas the loops and pins permit their opening as seen in Fig. 2. The combined width of the several blades when they are collapsed is not as great as the depth of the casing.

With this construction, and assuming that all parts are of metal or of material impervious to the weather, the signal stands about as seen in Fig. 1. When the operator desires to swing it out so as to display it, he grasps the handle 12 and raises the rod 9 a trifle so that he can move this rod to the left and pass its stop 13 through the left hand guide 10. This draws on the link 8 and the arm 7 and causes the main blade 11 to swing on its pivot 6. As it passes out of the casing or housing 3, the other blades 21 and 31 drop to the position shown in Fig. 2, or in other words the pin 26 travels down the loop 25 to the lower end of the latter, and the pin 28 travels down the loop 29 to its lower end. The signal might be said in this respect to resemble the blades of a fan, and the same falls open when the main blade assumes a substantially horizontal position. In any event the arm 22 at the lower end of each blade other than the main blade contacts with the back of the casing when

the spring throws the fan into the casing, thus causing the blades of the fan to close together and retained in such position against accidental displacement.

- 5 A reverse operation of the slide rod causes the main blade to again assume an upright position as seen in Fig. 1 and the several blades are housed within the casing and caused to overlie each other closely as shown. In this position they are practically housed and protected and in any event they cannot be seen from any direction. Assuming that both faces of the blades are painted some striking color, it may be discerned if only a portion of the face were exposed. But when housed as seen in Fig. 1, neither face can be seen at all from front or rear and the edge view displays no color as will be seen from Fig. 4. It is quite possible 10 that a signal of this kind could be provided on each end of a windshield, or in fact it might be attached to some other part of the automobile if preferred. Although not necessary to illustrate, it is quite obvious 15 that there could be more blades than three, or possibly less. The outer end of one of the blades could carry an index visible by day or it might carry a small electric light visible by night, or both. While I have 20 shown the handle 12 as lying along the lower side of the windshield frame F it could of course be carried to any convenient point for manipulation by hand or foot or perhaps mechanically. I reserve the widest 25 rights as to the uses to which this invention may be put, and while I have described it as applicable more especially to automobiles where I intend to use it, I do not wish to be limited in that respect.
- 30 The foregoing description and the drawings have reference to what may be considered the preferred or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. In an automobile signal, the combination with an upright casing adapted to be

attached to a windshield, the casing being open at its outer side and slotted in its bottom, a pair of ears extending from the bottom adjacent said slot, a signal adapted to be housed within said casing and having an arm depending through said slot, and a pivot pin through the arm and ears; of a 55 slide rod mounted in guides along the windshield and having a handle, stops on the rod adapted for engagement with said guides selectively, a contractile spring connecting the outer end of said rod with said arm near 60 the pivot of the latter, and a link pivotally connecting the rod with the arm at the lower end of the latter.

2. In a signal, the combination of an upright casing slotted in its lower end, a blade 70 adapted to stand within said casing and having an arm projecting through said slot, a main pivot connecting the arm with the casing below the bottom of the latter, and operating mechanism connected with said 75 arm, of a plurality of supplementary blades pivoted to the main blade above the main pivot, and means provided upon said blades for limiting their opening movement when the main blade is thrown outward.

3. In a signal, the combination of an upright casing having a top and bottom closure, said bottom closure slotted and provided with a pair of ears adjacent said slot, of a main blade having at its lower end an 80 arm extending through said slot and between said ears, a pivot pin through the ears and arm, operating connections at the lower end of said arm, a plurality of supplementary blades whose bodies lie along 85 side that of the main blade when housed within the casing and whose lower ends constitute an arm resting at that time on the bottom of said casing, a pivot connecting said blade above the said arms for the purpose specified, and means at the upper ends of the blades for limiting their opening 90 movement when the main blade is thrown outward.

In testimony whereof I affix my signature 100 in presence of two witnesses.

EDWIN CURTIS CLARK.
